CLAIM

The ornamental design for a wash basin, as shown and described.

DESCRIPTION

FIG. 1 is a front, right and top perspective view of a wash basin showing my design.

FIG. 2 is a front, right and top perspective view of the basin of the wash basin in FIG. 1.

FIG. 3 is a rear, left and bottom perspective view of the basin of FIG. 2.

FIG. 4 is a front elevation view of the basin of FIG. 2.

FIG. 5 is a rear elevation view of the basin of FIG. 2.

FIG. 6 is a left side elevation view of the basin of FIG. 2.

FIG. 7 is a right side elevation view of the basin of FIG. 2.

FIG. 8 is a top plan view of the basin of FIG. 2.

FIG. 9 is a bottom plan view of the basin of FIG. 2.

FIG. 10 is a front, right and top perspective view of the basket of the wash basin in FIG. 1.

FIG. 11 is a rear, left and bottom perspective view of the basket of FIG. 10.

FIG. 12 is a front elevation view of the basket of FIG. 10.

FIG. 13 is a rear elevation view of the basket of FIG. 10.

FIG. 14 is a left side elevation view of the basket of FIG. 10.

FIG. 15 is a right side elevation view of the basket of FIG. 10.

FIG. 16 is a top plan view of the basket of FIG. 10; and,

FIG. 17 is a bottom plan view of the basket of FIG. 10.

The broken lines shown in the drawings are included for the purpose of illustrating portions of the wash basin that form no part of the claimed design.
